PAPER FASTENER

Orland A. Krenke, Martins Ferry, Ohio

Application October 10, 1942, Serial No. 461,591

3 Claims. (Cl. 24—67)

The present invention relates to new and useful improvements in fasteners for holding several sheets of paper together and the invention has for its primary object to provide a non-metallic paper fastener of this character designed for use as a paper clip and embodying means for firmly securing the sheets of paper together without mutilation or injury thereto.

A further object of the invention is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout and in which:

Figure 1 is a fragmentary rear elevational view showing the paper fastener in position for securing the corner of two sheets of paper together.

Figure 2 is a similar view showing the front side of the fastener.

Figure 3 is a similar view showing the fastener in a partly open position.

Figure 4 is a sectional view taken substantially on a line 4—4 of Figure 1.

Figure 5 is a plan view of the fastener in its partially open position removed from the paper, and

Figure 6 is a plan view of the blank from which the fastener is formed.

Referring now to the drawing in detail wherein for the purpose of illustration I have disclosed a preferred embodiment of the invention, the numeral 5 designates the blank generally from which the fastener is constructed, the blank being composed of substantially stiff paper, or similar nonmetallic material and is preferably of rectangular form and includes a back portion 6 along the lower edge of the material at the corners of which are indicated the diagonally extending fold lines 7 connected at their inner ends by the transversely disposed fold line 8.

At the junction of the fold lines 7 and 8 the material is severed to form slits 9—9 which extend in diverging relation to form the flaps 10—10 adapted for folding along the fold lines 7 upon the bottom portion 6 as will be apparent from an inspection of Figure 5 of the drawing.

The outer edges of the flaps 10 are formed with slits 11 adapted for inter-connecting the flaps to secure the same against separation.

The material between the slits 9 forms a tongue 12 connected to the bottom portion 6 along the fold line 8 and the tongue 12 is provided at its outer edge with a flap 13 foldable along the fold line designated at 14.

After the flaps 10 have been folded upon the bottom portion 6 and secured in position the corner of the paper designated at 15 is inserted between the portion 6 and the connected flaps 10 in the manner indicated in Figure 3 of the drawing, the corner of the paper projecting through and beyond the flaps 10 to partly lie upon the tongue 12. The tongue 12 and the corner of the paper are then folded upon the flaps 10 and the extension 13 folded along the fold line 14 upwardly under the flaps 10 as will be apparent from an inspection of Figures 2 and 4 of the drawing.

In this manner two or more sheets of paper may be securely attached together to prevent separation thereof.

When it is desired to separate the paper the extension 13 of the tongue 12 is withdrawn from under the flaps 10 and the paper may then be withdrawn from the fastener.

It is believed the details of construction, advantages and manner of use of the device will be readily understood from the foregoing without further detailed explanation.

Having described the invention, what is claimed as new is:

1. A paper fastener comprising a sheet of foldable material including an elongated central portion, a pair of tabs at the side edges thereof and adapted for folding in overlapping relation upon the central portion, means for securing free ends of the tabs to each other to form a continuous flat band adapted for receiving a corner of a stack of paper sheets, a tongue on the upper edge of the central portion and foldable upon the tabs together with said corner of the paper, and a foldable extension on said tongue adapted for folding under the tongue and the tabs.

2. A paper fastener comprising a sheet of foldable material including an elongated central portion, a pair of tabs at the side edges thereof and adapted for folding in overlapping relation upon the central portion, said tabs having inter-engaging slits adapted for securing the tabs together to form a continuous flat band adapted for receiving a corner of a stack of paper sheets, a tongue on the upper edge of the central portion and foldable upon the tabs together with said corner of the paper sheets, and a foldable extension on the tongue adapted for engaging under the tongue and the tabs.

3. A paper fastener comprising a sheet of foldable material, tabs at the opposite side edges of the sheet foldable upon the sheet to form a continuous band adapted to receive a corner of a stack of paper sheets, means for securing the free ends of the tabs to each other, and a tongue on the sheet foldable upon and under the band for covering the connected ends of the tabs.
